UNITED STATES PATENT OFFICE.

JOSEPH B. HOWE, OF WORCESTER, MASSACHUSETTS, ASSIGNOR TO GEORGE S. HARWOOD & SON, OF BOSTON, MASSACHUSETTS, A COPARTNERSHIP CONSISTING OF SYDNEY HARWOOD, OF NEWTON, MASSACHUSETTS, AND JOHN H. HARWOOD, OF BROOKLINE, MASSACHUSETTS.

CARD-FEEDING MECHANISM.

Application filed November 16, 1926. Serial No. 148,688.

This invention pertains to feeding mechanism of carding machines and relates more particularly to automatic weighing mechanism for use in such machines.

For convenience of illustration the present invention is shown as applied to a Bramwell feeder provided with automatic weighing mechanism of the general character disclosed in the patent to Howe No. 1,531,944, dated March 31, 1925.

In my aforesaid patent I disclosed a dumping scale pan having a movable bottom wall or closure member and independent levers for causing said closure member to open and for restoring it to closed position respectively. In the same patent I also disclosed a pair of swinging abutment levers for damping the oscillations of the pan when the latter is restored to load receiving position after dumping.

The present invention relates to certain improvements in the mechanism disclosed in the aforesaid patent and particularly to the provision of a simplified construction in which the same moving part first causes the pan to open and subsequently closes it, said part also comprising means for damping the oscillations of the pan.

In the accompanying drawings:

Fig. 1 is an end elevation of a modified Bramwell feeder of the type disclosed in my aforesaid Patent No. 1,531,944, having the present improvements embodied therein;

Fig. 2 is a fragmentary end elevation to larger scale, showing the pan in load receiving position;

Fig. 3 is a view similar to Fig. 2 but showing the parts positioned in readiness for dumping the pan;

Fig. 4 is a view similar to Fig. 2 but showing the pan wide open and with the parts positioned in readiness for closing the pan and elevating the scale beam;

Fig. 5 is a view similar to Fig. 2 but showing the parts at the instant that the pan has been restored to load receiving position; and

Fig. 6 is a fragmentary section on the line 6—6 of Fig. 5.

For a more minute description of the details of construction of the machine as a whole, my prior Patents No. 998,003, July

18, 1911; No. 1,434,058, October 31, 1922; No. 1,531,944, March 31, 1925; and No. 1,531,945, March 31, 1925, may be referred to, but it is to be understood that the present invention is not necessarily limited to use in machines such as disclosed in said patents, but in its broader aspects may be found of utility in connection with dumping scale pans of other types and for other purposes.

Referring to the drawings, the numeral 1 indicates one end of the frame of a Bramwell feeder of substantially usual type. This feeder is provided with a bin 2 at its rear end for the reception of the fiber to be treated. A shaft 3 extends across the upper portion of the bin and supports a vibrating apron, not shown, while a shaft 4 is journaled at the upper rear portion 70 of the frame and supports and actuates an oscillating comb, not shown.

At the front of the machine a forwardly projecting bracket 5 is provided which supports an endless conveyor 6 which is driven by means of a shaft 7 receiving its motion from a carding machine, not shown, with which the machine herein disclosed is associated. A main drive shaft 8 is journaled in bearings in the lower part of the frame and this shaft is provided with a pulley or other driving means receiving its motion from any desired source, while a shaft 9 is journaled in bearings in the frame just above and to the rear of the main shaft 8

and is driven by means of a gear 10 carried by the main shaft. A pulley 11 is secured to the shaft 9. A shaft 12 is journaled in bearings at the upper part of the frame and this shaft is provided with a clutch mechanism, comprising a pulley 13 which is driven by means of a belt from the pulley 11. A shaft 14 extends across the frame at its lower part and is provided with a roller or other suitable means for guiding an endless spike apron which passes over a driving roller mounted on the shaft 12. At the front of the machine near its top a shaft 15 is journaled which receives intermittent oscillating motion from the shaft 12.

The clutch mechanism for driving the shaft 12 comprises a disengaging element 17 provided with projecting teeth 18, this clutch being, if desired, of the type dis-

closed in the patent to Howe No. 998,003, July 18, 1911. The disengaging element 17 is actuated to stop the shaft 12 by means of a counterweighted dog 19 which is normally held in inoperative position by means of a trip device 20, having an arcuate end engaging a lug 19^a on the dog. The other end of the trip device is connected to a rod 20^a passing downward through an opening in the arm 21 of the scale beam and is provided with a spring which bears resiliently against the arm.

The weighing mechanism comprises a composite scale beam consisting of like members such as 21 disposed at opposite sides of the machine and fulcrumed on supporting brackets such as 22. The members 21 are preferably counterweighted as indicated at 23 and are turned upwardly at 24^a their forward ends to provide bearings at 24 for the opposite ends of a pivotally supported scale pan 25.

This scale pan is of the dumping variety, open at the top and having front and rear walls 26 and 26^a and end walls 27. The bottom of the pan is normally closed and preferably comprises the bottom wall members or closures 28 and 28^a, respectively, which normally engage each other along their edges 29 and 29^a. The members 28 and 28^a are secured to shafts 30 and 30^a, respectively, journaled at the lower edges of the front and rear members 26 and 26^a.

The shafts 30 and 30^a are actuated to move the members 28 and 28^a to and from closed position by means of levers 31 and 32 respectively. Member 32 is provided at its rear extremity with an outwardly projecting actuating pin 33 which is received in an elongate slot 34 in the free extremity of the lever 31. Preferably the pin 33 is adjustable longitudinally of the lever 32, although this is not essential.

When the pan occupies the position shown in Fig. 2 the pin 33 is locked in the upper end of the slot 34 by means of a latch 37. This latch is pivoted upon a pin 36 carried by a bracket projecting from the lever 31 and is preferably provided with a counterweight 38 at its outer end tending to retain the latch in operative position. The latch is provided with an abutment shoulder 39 which normally engages the pin 33 to hold the latter in the upper end of the slot in the lever 31 as indicated in Fig. 2.

The latch also comprises a releasing arm 40 provided with a substantially horizontal toe portion 41. Depression of this toe portion 41 below its normal position raises the arm 37 and releases the shoulder 39 from the pin 33, permitting the latter to slide along the slot in the arm 31, thus allowing the closure members 28 and 28^a to open, dumping the contents of the pan.

A shaft 41^a is journaled in suitable bear-

ings in the end frame of the machine and a gear 42 is secured to this shaft. This gear meshes with a gear 43 mounted on a stub shaft 44 secured to the end frame of the machine. A sprocket wheel is connected to 70 the gear 43 and is driven by means of a chain 45 which passes about a sprocket wheel on the shaft 7.

The shaft 44 is furnished with a pair of angularly disposed crank arms 46 and 47, 75 respectively, provided with crank pins preferably consisting of freely turning rolls 48 and 49, respectively.

A shaft 50 is secured to the machine frame at a point above and slightly forward of the shaft 44 and upon this shaft a lever 51 is mounted. This lever is provided with a bracket 53 carrying the laterally projecting pin 52 disposed substantially above the toe 41 of the latch-releasing arm 40 although normally the pin 52 is spaced from the toe 41 so that it does not in any way interfere with the freedom of movement of the pan during weighing.

Preferably, although not necessarily, I 90 mount a bracket 54 (Fig. 3) upon the upper edge of the lever 51 near the end of the latter and provide the bracket with an open recess or notch 55 constituting a socket for the reception of the projecting actuating pin 33 above referred to. The socket 55 is normally disposed below the pin 33 and in a position such that when the scale beam has tipped and the pan has opened, the pin 33 is just above or within the socket but 100 preferably without bottoming against the lower surface of the socket.

Preferably the lever 51 comprises two parts which are adjustably connected by a bolt and slot connection at 56, but this construction is not essential and forms no necessary part of the present invention.

The lever 51 is furnished with an arm 57 which is provided with cam surfaces 58 and 59. The cam surface 59 is normally disposed in the path of the roll 49 carried by the crank arm 47, the shape of the cam surface 59 being such that as the crank arm 47 turns in a clockwise direction it moves the cam surface 59 inwardly toward the shaft 110 44, thus swinging the lever 51 in a counter-clockwise direction.

The cam surface 58 is disposed in the path of the roll 48 carried by the crank arm 46 and is so arranged that as the crank arm 120 turns, the arm 57 and lever 51 are turned in a clockwise direction. As the crank arms 46 and 47 are angularly spaced, they act successively upon the lever 51, thus positively oscillating the latter in opposite directions.

Preferably I mount another lever 60 upon the shaft 50 which supports the lever 51 and provide the lever 60 with an arm 61 having an adjustable abutment 62 engaging 125

the under side of the arm 51. The lever 60 is provided at its rear end with a counter-weight 63 which substantially balances the lever 51 and the parts carried thereby so as to hold the lever 51 normally in the position shown in Fig. 2. A stop pin 64 may be provided for limiting the downward swing of the lever 60, but since the lever arm 51 rests freely upon the abutment 62, 10 the arm 51 may be lifted freely above the position shown in Fig. 2, thus moving away from the stop 62.

A third lever 65 is, in the present instance, mounted upon the shaft 50, and this lever 15 is provided with a cam surface (not shown) which is also engageable by the roller 48. The lever 65 is furnished with an arm 67 (Fig. 2) carrying a pin 68 engaging an elongate slot 69 in the rod 79 which, as more 20 fully described in my Patent No. 1,531,944, constitutes means for resetting the dog 19.

In the operation of the machine and while the scale pan is being filled the shaft 44 is turning slowly, but the crank arms 46 and 25 47 are moving through that portion of their path remote from the lever arms 57 and 65. When the pan has received its proper load it tips the scale beam downwardly until the beam occupies the position indicated in Fig. 30 3. At about this time, or slightly thereafter, the roll 49 engages the cam member 59 and begins to swing the lever arm 57 in a counter-clockwise direction. The arm 51 is thus moved in the same direction until the pin 35 53 engages and depresses the toe 41 of the latch-releasing arm 40. The latch arm 37 is thus swung upwardly, thereby releasing the pin 33 and permitting the scale pan to open as shown in Fig. 4, dumping the material 40 onto the traveling conveyor 6. If the counterweight 23 on the scale beam be heavy enough, the scale beam may now swing upwardly toward load receiving position, the scale pan still being open. However, I 45 prefer to arrange the counterweight 23 so that when the pan is dumped it remains at its lowermost position until mechanically raised.

Soon after the pan has been opened, the 50 roller 48 comes into engagement with the cam surface 58, it being understood that the roller 49 has previously disengaged the cam surface 59. Continued movement of the crank arm 46 swings the lever arm 57 in a 55 clockwise direction, thus swinging the arm 51 upwardly. The notch 55 engages the pin 33 sooner or later and the continued movement of the lever 51 gradually closes the pan, at the same time lifting the pan and moving 60 the scale beam toward normal position. The lever 51 continues to move upwardly until it has passed its normal position and reached the position indicated in Fig. 5. At this 65 point the pin 33 has been restored to the upper end of the slot in the lever arm 31

and the latch 37 is free to drop behind the pin 33, thus retaining the bottom members of the pan in closed position, the scale beam engaging a stop 70 which limits its upward movement. 70

The pin 33 is spaced a substantial distance from the fulcrum point 24 of the scale pan and substantially in the vertical plane of such fulcrum, and as the notch 55 of the lever 51 moves in a predetermined path and as the pin 33 is embraced by this notch, it is evident that the pin 33 must move in a substantially fixed path during its upward travel so that the pan is prevented from oscillating about its fulcrum. Since the pin 33 remains in 80 the notch 55 until the pan has been fully restored to load receiving position, it is substantially impossible for the pan to oscillate to any substantial degree, and if slight oscillations are set up, the side walls of the 85 notch 55 engage the pin 33 so as to damp such oscillations.

When the cam roll 48 disengages cam surface 58 the lever 51 drops back to its normal position wherein it is spaced from the pin 33 and also from the toe 41 of the latch-releasing lever. The parts are thus restored to normal position and are ready to receive another load of material. 90

In usual manner the operation of lever 65, 95 through the rod 79, resets the dog 19 so that the shaft 12 which was stopped by the downward tipping of the scale beam is now restored to action and fiber is again fed into the scale pan preparatory to a second weighing operation. 100

I claim:

1. A machine of the class described comprising a scale beam, a dumping scale pan supported thereby, a movable closure for the pan, a lever operative both to initiate opening of said closure and to restore the closure to normal closed position, and power actuated means for positively moving said lever alternately in opposite directions. 105

2. A machine of the class described comprising a scale beam, a dumping scale pan supported thereby, a movable closure for the pan, a power driven shaft, a lever, and co-operating elements carried by the shaft and lever respectively for positively moving the lever alternately in opposite directions whereby to initiate opening of said closure and to restore the closure to closed position, respectively. 110

3. A machine of the class described comprising a scale beam, a dumping scale pan supported thereby, a movable closure for the pan, a single lever for initiating opening of the closure and for restoring the closure to normal position, a pair of cam elements carried by the lever, a power driven shaft, and spaced members carried by said shaft, said members successively engaging the respective cam elements thereby posi- 115 120 125 130

- 55 tively to oscillate the lever in opposite directions.
4. A machine of the class described comprising a scale beam, a dumping scale pan supported thereby, a movable closure for the pan, a power driven shaft, angularly spaced crank arms carried by the shaft, each arm having a crank pin, and a single lever for initiating opening of the closure and for restoring the closure to normal position, said lever having an arm provided with cam surfaces eccentric to the axis of the shaft and engageable by the respective crank pins whereby to oscillate the shaft.
- 15 5. A machine of the class described comprising a scale beam and a scale pan supported thereby, the pan having a movable closure, latch means normally operative to retain the closure in closed position, said latch means comprising an actuating pin and a releasing arm, a lever having parts normally disposed below and above but spaced from the actuating pin and releasing arm respectively, a counterweight for holding the lever in normal position, a power driven shaft, and angularly spaced members carried by the shaft and successively engaging portions of the lever for oscillating the lever.
- 30 6. A machine of the class described comprising a scale beam supporting a dumping scale pan having a latch controlled closure, a single lever operative, after the scale beam has tipped in response to a load in the pan, first to release the latch whereby to permit the closure to open, and subsequently to restore the scale beam to normal position and to close the pan and to close the pan and reset the latch, and power actuated means for moving the lever alternately in opposite directions.
- 45 7. A machine of the class described comprising a scale beam and a scale pan supported thereby, the pan having a movable closure, latch means normally operative to retain the closure in closed position, said latch means comprising an actuating pin and a releasing arm, and a lever having parts normally positioned below and above the actuating pin and releasing arm, respectively, and means for first swinging the lever below and then above its normal position.
- 50 8. A machine of the class described comprising a dumping scale pan having a movable closure, latch means normally retaining the closure in closed position, said latch means having releasing and resetting elements, and means for releasing the latch means comprising a lever having parts normally above and below the releasing and resetting elements, respectively, and power actuated means for moving the lever in one direction whereby to engage one of said parts with the releasing element, and for there- 65 after moving the lever in the opposite direc-
- tion whereby to engage the other of said parts with the resetting element whereby to restore the closure to normal position and reset the latch.
9. A machine of the class described comprising a scale beam and a scale pan supported thereby, the pan having a movable closure, latch means normally operative to retain the closure in closed position, said latch means comprising an actuating pin and a releasing arm, a lever having a lateral projection normally disposed above said releasing arm, the lever also having an element disposed below said pin, and power actuated means for swinging the lever alternately in opposite direction.
10. A machine of the class described comprising a scale beam and a scale pan supported thereby, the pan having a movable closure, latch means normally operative to retain the closure in closed position, said latch means comprising an actuating pin and a releasing arm, a lever having parts engageable alternately with the releasing arm and actuating pin respectively, cam elements carried by the lever, and means engageable with said cam elements for positively oscillating the lever in opposite directions.
11. A machine of the class described comprising a scale beam, a dumping scale pan fulcrumed upon the beam, an abutment member carried by the pan, a single lever having a part cooperable with said abutment to restore the beam to normal position after it has tipped in response to a load in the pan, said abutment and cooperating part being so relatively shaped as to damp oscillations of the pan about its fulcrum on the beam, and means for swinging the lever to bring said abutment and cooperating part into engagement.
12. A machine of the class described comprising a scale beam, a dumping scale pan fulcrumed on the beam, said pan being provided with a normally closed closure member, a lever operative first to initiate opening of the closure member and subsequently to restore the scale beam to normal position, after it has tipped in response to a load in the pan, and to damp oscillations of the pan about its fulcrum on the beam, and power actuated means for moving said lever alternately in opposite directions.
13. A machine of the class described comprising a scale beam, a scale pan fulcrumed upon the beam, an abutment projecting from the pan at a point spaced from the fulcrum, and means constraining said abutment to move in a predetermined path while the beam is returning to normal position, after tipping in response to a load in the pan, whereby substantially to prevent oscillations of the pan about its fulcrum on the beam.
14. A machine of the class described com-

prising a scale beam, a scale pan fulcrumed upon the beam, a pin projecting from the pan at a point spaced from the pan fulcrum, a lever having an element provided with a notch for receiving said pin, and means operative, after the beam has tipped in response to a load in the pan, to move the lever whereby to engage the notch with the pin and restore the beam to normal position while preventing oscillation of the pan about its fulcrum on the beam.

15. A machine of the class described comprising a scale beam, a scale pan fulcrumed on the beam, a pin projecting from the pan at a point spaced from and substantially in the vertical plane of the fulcrum of the pan, a member having a socket notch for the reception of said pin, and means for moving

said member in a predetermined path, while the pin is confined in said notch, whereby 20 to return the beam to normal position, after it has tipped in response to a load in the pan, while substantially preventing oscillation of the pan about its fulcrum on the beam.

16. A machine of the class described comprising a scale beam, a dumping scale pan fulcrumed upon the beam, an abutment pin carried by the pan, a member having a notch for receiving said pin, and means for moving said notched member into engagement with the abutment pin whereby to damp oscillations of the pan about its fulcrum on the beam.

Signed by me at Worcester, Massachusetts, this 26th day of October, 1926.

JOSEPH B. HOWE.
